UNITED STATES PATENT OFFICE.

PHILANDER H. GRAVES, OF CHICAGO, ILLINOIS.

ELASTIC HORSESHOE.

SPECIFICATION forming part of Letters Patent No. 591,601, dated October 12, 1897.

Application filed April 24, 1897. Serial No. 633,646. (No model.)

To all whom it may concern:

Be it known that I, PHILANDER H. GRAVES, a citizen of the United States, residing at Chicago, in the county of Cook and State of Illinois, have invented certain new and useful Improvements in Horseshoes; and I do hereby declare the following to be a full, clear, and exact description of the invention, such as will enable others skilled in the art to which it appertains to make and use the same:

This invention relates to horseshoes, and has for its object to provide an elastic or resilient horseshoe having removably fitted and embedded therein a metal strip or reinforcement constituting an inelastic frame, through which the nails or other fasteners pass, by means of which the shoe is secured to the animal's hoof, the arrangement being such that the said strip or frame is located wholly within the plane of the shoe proper, so as to cause the heads of the nails to be incased between the side portions of the shoe where they afford no projections.

The improved horseshoe is also provided on both surfaces and at the toe and heel with reinforcing wear-plates, the purpose of which will be hereinafter described.

The invention consists in a horseshoe embodying certain novel features and details of construction and arrangement of parts, as hereinafter fully described, illustrated in the drawings, and incorporated in the claims here-to appended.

In the accompanying drawings, Figure 1 is a perspective view of a horseshoe constructed in accordance with this invention, looking from the under side. Fig. 2 is a similar view with the inelastic strip or frame omitted. Fig. 3 is a detail section taken through the toe of the shoe. Fig. 4 is a similar section taken through the heel of the shoe. Fig. 5 is a detail perspective view of the heel portion of the shoe, showing a slight modification.

Similar numerals of reference designate corresponding parts in the several figures of the drawings.

Referring to the drawings, 1 designates the main body of the shoe, which may be of any suitable size and shape and which is composed of rubber or analogous material. The

toe of the shoe is increased in width and provided with a rearwardly-projecting V-shaped extension 2, giving to the shoe a heart shape and increasing the wearing and bearing surface of the shoe at the toe portion. Upon 55 its under side the shoe is provided with a continuous groove 3, extending from one heel portion to the other, the ends of the groove terminating just short of the extremity of the heel portions sufficiently to leave room 60 for a pair of heel-plates, hereinafter described.

Within the groove 3 is a metal strip or frame 4, corresponding in length and shape to the groove, said strip or frame being convex in cross-section, with its rounded side disposed inward and fitting snugly the rounded base or floor of the groove 3. The outer or flat side of said strip or frame is located within the plane of the bottom of the shoe, so as to prevent the nails from projecting below the lower surface of the shoe. At suitable points the strip or frame 4 is provided with openings 5 to receive the nails, and these openings are countersunk, so as to let the heads of the nails lie flush with the frame 75 or strip. The strip is made of less thickness than the depth of the groove 3, so that the edges 7 of the shoe will project below the bottom surface of such strip or frame, thus forming ribs, which will engage the ground and 80 guard against the lateral slipping of the shoe when traveling upon smooth and wet or icy surfaces. The strip or frame 4, instead of being exactly in the form of a horseshoe, has its central portion deflected or given a backward V-shaped offset, as indicated at 8, so as to make room for a toe-plate 9.

The toe-plate 9 consists of a single piece of sheet metal which is bent so as to lie under the toe portion of the rubber shoe, the front 90 edge of said plate being bent around and upward in front of the toe portion of the shoe and having its edge rolled, as indicated at 10, and embedded in the rubber, as clearly shown in the sectional view, thus preventing any 95 possibility of the toe-plate becoming detached. The rear portion of the plate 9 is pressed inward, so as to conform to the groove 3, as indicated at 11, and is extended along the rear portion of the groove and embedded in the 100

rearwardly-projecting extension at the center of the toe portion of the shoe, as indicated at 12. The toe-plate 9 is thus held securely in place, and in addition to forming a reinforcement for the toe-plate, which adds greatly to the life and durability of the shoe, said plate also affords a bearing for the toe portion of the strip or frame 4. Upon the upper side of the shoe at the toe portion is arranged a bearing-plate 13, which has its end portions rolled and embedded in the rubber similarly to the toe-plate 9, the plate 13 lying flush with the upper surface of the shoe and forming a bearing for the toe of the hoof. Other bearing-plates 14 are located at the heel ends of the shoe and are intended to receive the heel portions of the hoof, so as to prevent the same from cutting into the rubber and effecting a too rapid wearing away of the same. The plates 14 are held in place by rolling their end portions and embedding them in the rubber in a manner hereinbefore described.

15 designates a pair of heel-plates which consist of sheet metal, each having its corners rolled and embedded in the rubber of the shoe adjacent to the heel ends thereof, said plates 15 lying flush with the under side of the shoe and serving to take the excessive wear occurring at such points.

30 By means of the construction above described it will be seen that a resilient horseshoe is obtained which will absorb all jar and vibration and prevent the same being imparted to the hoofs and legs of the animal. 35 It will also be seen that the peculiar construction described renders the slipping in any direction unlikely, thus adapting the shoe particularly for wet and icy weather and obviating the necessity for using calks. The construction described also combines simplicity and durability and will outlast many sets of calks, the shoe preventing any slipping as long as it lasts.

The toe and heel plates prevent too rapid 45 wearing away of the rubber and greatly increase the life of the shoe, as the rubber will wear away no faster than the said reinforcing-plates. By making the metal strip or plate of less depth than the groove in which it fits 50 not only are the heads of the nails concealed and prevented from projecting beyond the plane of the shoe, but oppositely-located ribs are provided which serve to prevent the slipping of the shoe.

55 In addition to the advantages above enumerated the shoe as a whole is to a certain extent flexible laterally, so that it may accommodate the natural growth of the animal's foot and not cause too great contraction 60 thereof, which, as is well understood, is extremely injurious to the animal. The light metal frame or strip permits the shoe to shape itself to the animal's foot, and the shoe as a whole forms an agreeable cushion to the animal's foot, which is especially desirable when

traveling upon asphalt or stone pavements. The upper and lower plates are preferably formed of spring-steel, and the rolled or curled edges of said plates lie apart and separate from each other and do not interfere with the elasticity of the shoe as a whole. By this construction a practically noiseless shoe is produced.

If desired, the heel-plates 15 may be formed integrally with the frame 4, the ends of the frame being expanded or widened to form the heel-plates. It may also be desirable to provide a continuous groove in the lower surface of the frame 4 instead of countersinking the openings 5 to receive the nails, the groove 80 serving to admit the heads of the nails, as shown in Fig. 5.

Having thus described the invention, what is claimed as new is—

1. A horseshoe composed of rubber and having at its toe portion a rearwardly-projecting V-shaped extension giving increased width and bearing-surface to said toe portion, said shoe being provided in its under side with a groove extending from heel to heel, in combination with a metal strip or frame having a central V-shaped offset and located in said groove which is of corresponding shape and provided with openings for the reception of attaching means, substantially as described. 95

2. A horseshoe composed of rubber and provided in its under side with a groove, in combination with a metal strip or frame located in said groove and having openings for the reception of attaching means, and a toe-plate 100 formed from sheet metal and embracing the toe portion of the shoe, said toe-plate extending around the under side of the shoe and having its edge curled or rolled and embedded in the rubber, substantially as described. 105

3. A horseshoe provided in its under side with a groove, in combination with a metal strip or frame located in said groove and provided with openings for the attaching means, and a toe-plate formed of sheet metal bent 110 around the under side of the shoe and having its front edge curled or rolled and embedded in the rubber, said plate being also deflected or curved in the plane of the base of the groove so as to form a seat or bearing-surface for 115 the metal strip or frame, substantially as described.

4. A horseshoe composed of rubber and provided along its under side with a groove, in combination with a metal strip or frame fitted in said groove and provided with openings for the attaching means and a pair of heel-plates each consisting of a piece of sheet metal having its corners or edges rolled and embedded in the rubber, said heel-plates being flush with the under side of the shoe, substantially as described. 125

5. A horseshoe composed of rubber and provided in its under side with a groove, in combination with a metal strip or frame arranged 130

in said groove and having openings for the attaching means, and bearing-plates on the upper side of the shoe arranged at the toe and heel end thereof, said plates having their edge portions rolled and embedded in the rubber, substantially as described.

In testimony whereof I have signed this

specification in the presence of two subscribing witnesses.
